The ornamental design for an opaque aerosol dispenser, as shown and described.

DESCRIPTION

FIG. 1 is a rear perspective view showing our new design for an opaque aerosol dispenser;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a plan view of the top thereof; and,

FIG. 7 is a plan view of the bottom thereof.

The broken lines are included for the purpose of illustrating elements of the aerosol container that, together with the unshaded region in FIG. 7 form no part of the claimed design.
